Patented Sept. 7, 1920.

UNITED STATES PATENT OFFICE.

WALTER MCKENZIE, OF TULSA, OKLAHOMA.

TOOL-HANDLE.

1,352,012.

Specification of Letters Patent. Patented Sept. 7, 1920.

Application filed May 25, 1918. Serial No. 236,571.

To all whom it may concern:

Be it known that I, WALTER MCKENZIE, a citizen of the United States, residing at Tulsa, in the county of Tulsa and State of Oklahoma, have invented certain new and useful Improvements in Tool-Handles; and I do hereby declare the following to be a full, clear, and exact description of the invention, such as will enable others skilled in the art 10 to which it appertains to make and use the same.

This invention relates to improvements in tool handles and has for one of its objects the provision of a device of this character, 15 whereby a plurality of wires may be utilized to construct the handle so as to render it of an increased durability over other handles that are used for tools and which will have such resiliency that it will take up shocks 20 and jars caused thereto when used in connection with hammers and like tools.

Another object of this invention is the provision of the wires intertwined in opposite directions to form a strong body to the 25 handle and having the ends of the wires arranged in elliptical formation so as to provide an efficient hand grip portion and a portion to receive the tool.

A further object of this invention is the 30 provision of a tool handle of the above stated character, which shall be simple, durable and efficient, and which may be manufactured and sold at a comparatively low cost.

With these and other objects in view as 35 will become more apparent as the description proceeds, the invention consists in certain novel features of construction, combination, and arrangement of parts as will be hereinafter more fully described and 40 claimed.

For a complete understanding of my invention, reference is to be had to the following description and accompanying drawing, in which:

45 Figure 1 is a side elevation partly in section of a tool handle constructed in accordance with my invention.

Fig. 2 is a longitudinal sectional view of the same.

50 Fig. 3 is a transverse sectional view of the hand grip.

Fig. 4 is a similar view of the end portion which receives the tool.

Referring in detail to the drawing, the 55 numeral 1 indicates as an entirety a tool handle which is adapted for use in connec-

tion with various tools such as hammers, hatchets, and axes. The handle 1 consists of a body portion 2, a hand grip portion 3 and a portion 4 adapted to fit within a tool, 60 and in this instance, a hammer 5. The handle 1 is constructed from a plurality of wires 6, constructed from steel or other material suitable for the purpose. The wires are intertwined in opposite directions to 65 form the body 2 and the ends thereof are arranged in straight lengths 7 and in elliptical formation. The convolutions of the intertwined lengths or portions of the wires which form the body 2 of the handle, decrease in size from each end of the body so 70 as to make the intermediate portion of said body of a comparatively thin thickness, thereby rendering a neat appearance to the handle and one of great strength.

75 The lengths of wires which form the hand grip 3 have shrunk thereon a shell 8 constructed from aluminum or other material suitable for the purpose which provides an efficient hand grip. The other lengths of 80 straight wires are inserted in the eye of the hammer 5 and a wedge 9 may be driven therein for securing them tightly in the eye.

From the foregoing description taken in 85 connection with the accompanying drawing, it will be noted that a handle has been provided which can be readily and cheaply manufactured and one that will have an increased life over other tool handles of 90 similar nature and used for similar purposes.

While I have shown and described the preferred embodiment of my invention, it will be understood that minor changes in 95 construction, combination and arrangement of parts may be made without departing from the spirit and scope of the invention as claimed.

Having thus described my invention, what 100 I claim is:

A handle comprising an annular series of wires intertwined into a coil formation of smaller diameter intermediate of its length, the wires at the ends of the coil being continued straight and parallel with each other.

105 In testimony whereof I affix my signature in presence of two witnesses.

WALTER MCKENZIE.

Witnesses:

DONALD A. McLEOD,
CHUC DUNLAP.
